UNITED STATES PATENT OFFICE.

ADOLF KUYLENSTJERNA, OF PHILADELPHIA, PENNSYLVANIA.

CONDENSER.

No. 927,251.

Specification of Letters Patent.

Patented July 6, 1909.

Application filed March 16, 1909. Serial No. 483,789.

To all whom it may concern:

Be it known that I, ADOLF KUYLENSTJERNA, a subject of the King of Sweden, residing at Philadelphia, county of Philadelphia, State of Pennsylvania, have invented certain new and useful Improvements in Condensers; and I do hereby declare the following to be a full, clear, and exact description of the invention, such as will enable others skilled in the art to which it appertains to make and use the same.

My invention relates to improvements in condensers, and it is especially intended to provide a combined surface and jet condenser located at a sufficient height above the hot well to make use of the well-known barometric principle.

My invention will be understood by reference to the accompanying drawings, in which the same parts are indicated by the same letters throughout the several views.

Figure 1 shows a side elevation of the condenser, with the hot well shown in section and the various connecting pipes broken away. Fig. 2 shows the condenser proper on an enlarged scale, parts being shown in section along the vertical axes of the condenser.

A represents the outer shell of the condenser, which may be constructed of a series of castings, or of steel plates riveted together, and which is generally cylindrical in cross-section, with the top and bottom in the form of truncated cones. This shell A, with the parts contained therein, is mounted on a frame B, carried by the supports C, the heights of which supports, at sea-level, would be approximately thirty-four feet above water level in hot well, and less at higher altitudes, depending upon the maximum barometric pressure to which the condensed water and the cooling water would be subjected in outflowing.

The bottom cone A' of the shell A is provided with a series of radial ribs A², which serve as supports for the inner shell D, and separate the same sufficiently from the bottom shell A' to let the cooling water pass freely between the two shells into the tail pipe M. The sides of this shell D are cylindrical, and the upper portion D² is preferably in the form of a hollow truncated cone, open as at D³. Secured in this shell D is an annular diaphragm E surrounding the water tubes H, which are arranged in circular form in the heads G and I. The head G is secured to the flanges of the basin F, and forms a top for

said basin. The bottom of this basin rests on ribs D³ in the bottom of the shell D, so that the water of condensation can pass freely between the bottom of the basin F and the bottom of the shell D.

The upper head I of the water tubes H supports a hopper I', whose outer edge projects over the part D² of the shell D. Mounted above this head I is an inverted funnel K², preferably circular in cross-section, whose lower end rests on the head I, and incloses the upper end of a plurality of the water tubes located near the center of the system. This funnel K² is connected by the pipe K' to the cold water pipe K for supplying the condensing water. An expansion joint K⁰ is provided in the pipe K'. The pipe L is connected to the exhaust of the engine or engines or other apparatus supplying the steam to be condensed.

M represents the tail pipe for drawing off the water supplied for condensing purposes, and N represents the pipe for carrying off the water of condensation, or the "sweet water."

O represents a pipe connected to a suitable air-pump, not shown, and O' represents a splash guard to prevent any of the liquid contents of the apparatus from being sucked into the air pipe O.

P represents the hot well, which is preferably divided by the partition P' into two chambers P² and P³. Into the chamber P² the tail pipe M empties, and the overflow is drawn off by the pipe Q. The chamber P³ is provided with an upwardly-projecting diaphragm p, and a downwardly-projecting diaphragm p', the two forming a grease trap, the grease flowing to the surface, and the sweet water is drawn off through the pipe R. The partition P' is perforated, as at p⁰, to permit the overflow of the distilled water and the grease into the chamber P³, when the supply of said water becomes excessive.

The operation of the device is as follows:— The cooling water flowing in the direction of the plain arrows enters through the pipe K, passes down in the funnel K², flows downward through the central series of tubes H into the receptacle F, then up through the outer series of tubes into the hopper I', then overflowing said hopper drops on the conical surface D² of the chamber D. Such as splatters off is deflected back to said shell by the deflector A⁴, and this water running down the shell D, and between it and the shell A, finally escapes through the tail pipe M. The

path of the cooling water is indicated by plain arrows. The path of the vapor on the other hand is indicated by barbed arrows. This vapor enters through the exhaust pipe 5 L into the shell D, and the central series of the tubes H having the colder water, the tendency of this vapor is to flow inward toward the center of said group of tubes, where the aqueous vapor is condensed, and the air 10 and rarefied vapor flow upward and outward through the opening between the top of the shell D and the hopper I', passing upward to the pipe O, where it is drawn off by the vacuum pump, not shown. The tendency 15 of the vapor to flow inward toward the center of the group of tubes H is augmented by the annular diaphragm E. The distilled water drops down on the bottom of the chamber D, and escapes through the sweet 20 water tail pipe N, flowing into the sweet water chamber P' of the hot well, where the grease is trapped off, and the fresh water fed to the boilers through the pipe R. The vacuum pipe O opens into the part A³ of the 25 condenser near its highest part, and the drain pipes M and N lead from the bottom of their respective chambers. Thus the air remaining in the system is drawn off in a dry state, and the water, both the cooling and 30 the distilled water, is allowed to flow off through gravity.

It will be seen that the apparatus hereinbefore described comprises a surface condenser located in the center of an annular 35 jet condenser, the same cooling water being used for both.

It will be noted that the vacuum is the same on the inside as on the outside of the tubes H, and therefore a leaky tube will have 40 no effect on the vacuum. Again, the upper head I is free to rise or fall as the tubes expand or contract, which motion is permitted by the expansion joint K², and for this reason all the tubes can be expanded into the 45 tube heads like boiler tubes, and there is no necessity for ferrules, thimbles, stuffing boxes, or the like, such as are used in many surface condensers at present manufactured. It will be noted that no wet air pump is needed 50 to get the water out of the condenser.

As is well known, a surface condenser requires more cooling water than a jet condenser, because the tubes are not as effective as where the steam comes in direct contact 55 with the cooling water.

My invention provides for a combination of the two forms of the condenser, so that most of the actual condensation is effected in the tubes, while the remainder results 60 from the direct contact of the vapor with the cooling water, so that the higher efficiency of the jet condenser is secured, but at the same time most of the evaporated water is condensed and is kept separate for use over 65 again in the boilers.

In power plants, especially electric railway plants, where the load varies within wide limits, if a surface condenser alone be used, it must be very large and costly, in order to secure the requisite cooling surface, 70 but my idea is to arrange the surface condenser for the normal load, and let all the overloads be taken care of by the jet. The amount of the circulating water can be regulated to whatever is needed by varying the speed of the circulating pump. By having the shell A sufficiently elevated, the well-known advantages of the barometric tube jet condenser are secured, and at the same time by the herein described construction 75 the greater portion of the water evaporated is separated out in the form of distilled water which is suitable for use over again in the boilers. It will be noted that the vacuum acting on the upper end of the outer series of tubes H will tend to suck water down from the funnel K² and therefore this vacuum will assist the pump in forcing the water up through the pipe K.

The herein described device is believed to be simple in construction and economical and efficient in operation.

It will be obvious that various changes might be made in the herein described construction which could be used without departing from the spirit of my invention.

Having thus described my invention, what I claim and desire to secure by Letters Patent of the United States is:—

1. A condenser comprising an outer shell, an inner shell inclosed therein and spaced therefrom, a surface condenser mounted in said inner shell and delivering the distilled water to the inner shell and the cooling water to the outer shell, an exhaust pipe opening into the inner shell, a suction pipe connected to the top of the outer shell, a tail pipe for the cooling water connected to the bottom of the outer shell, and a tail pipe for the distilled water connected to the bottom of the inner shell, substantially as described.

2. A condenser comprising an outer shell, an inner shell inclosed therein and spaced therefrom, a surface condenser mounted in said inner shell and delivering the distilled water to the inner shell and the cooling water to the outer shell, an exhaust pipe opening into the inner shell, a suction pipe connected to the top of the outer shell, a tail pipe for the cooling water connected to the bottom of the outer shell, a tail pipe for the distilled water connected to the bottom of the inner shell, and a hot well divided into two compartments for the cooling water and the distilled water, respectively, located at a greater distance below the bottom of the outer shell than the height of a column of water maintained at normal barometric pressure, substantially as described.

3. A condenser comprising an outer shell,

- an inner shell inclosed therein and spaced therefrom, a surface condenser mounted in said inner shell and delivering the distilled water to the inner shell and the cooling water to the outer shell, an exhaust pipe opening into the inner shell, a suction pipe connected to the top of the outer shell, a tail pipe for the cooling water connected to the bottom of the outer shell, a tail pipe for the distilled water connected to the bottom of the inner shell, and a hot well divided into two chambers for the cooling water and the distilled water, respectively, located at a greater distance below the bottom of the outer shell than the height of a column of water maintained at normal barometric pressure, the said hot well being provided with an overflow passage from the top of the distilled water chamber, and a draw-off pipe from the lower part of said chamber, substantially as described.
4. An apparatus of the character described, comprising a hot well divided into two compartments, one for the cooling water and one for the distilled water, an outer shell mounted above said hot well at a greater height than a column of water balanced by atmospheric pressure, an inner shell supported in and spaced apart from said outer shell, tail pipes connecting the bottom of said inner and outer shells, respectively; and the two compartments of said hot well, a basin mounted in said inner shell, a bottom plate covering the top of said basin, water tubes secured in said plate and opening into said basin, a top plate secured to the upper end of said tubes, and spaced away from said inner shell, a hopper secured to said top plate and extending beyond the outer edge of the open top of said inner shell, an inverted funnel mounted upon the said top plate and surrounding the upper ends of a plurality of said water tubes, means for supplying cooling water to said funnel, an exhaust pipe opening into said inner shell, and a suction pipe connected to said outer shell, substantially as described.
5. An apparatus of the character described, comprising a hot well divided into two compartments, one for the cooling water and one for the distilled water, an outer shell mounted above said hot well at a greater height than a column of water balanced by atmospheric pressure, an inner shell supported in and spaced apart from said outer shell, tail pipes connecting the bottom of said inner and outer shells, respectively, and the two compartments of said hot well, a basin mounted in said inner shell, a bottom plate covering the top of said basin, water tubes secured in said plate and opening into said basin, a top plate secured to the upper end of said tubes, and spaced away from said inner shell, an inverted funnel mounted upon the said top plate and surrounding the upper ends of a plurality of said water tubes, a water pipe connected to said funnel, an expansion joint in said pipe, an exhaust pipe opening into said inner shell, and a suction pipe connected to said outer shell, substantially as described.
6. An apparatus of the character described, comprising a hot well divided into two compartments, one for the cooling water and one for the distilled water, an outer shell mounted above said hot well at a greater height than a column of water balanced by atmospheric pressure, an inner shell supported in and spaced apart from said outer shell, deflectors arranged between said inner and outer shells for directing the course of the cooling water, tail pipes connecting the bottom of said inner and outer shells, respectively, and the two compartments of said hot well, a basin mounted in said inner shell, a bottom plate covering the top of said basin, water tubes secured in said plate and opening into said basin, a top plate secured to the upper end of said tubes, and spaced away from said inner shell, a hopper secured to said top plate and extending beyond the outer edge of the open top of said inner shell, an inverted funnel mounted upon the said top plate and surrounding the upper ends of a plurality of said water tubes, means for supplying cooling water to said funnel, an exhaust pipe opening into said inner shell, and a suction pipe connected to said outer shell, substantially as described.
7. An apparatus of the character described, comprising a hot well, an outer shell mounted above said hot well at a greater height than a column of water balanced by atmospheric pressure, an inner shell supported in and spaced apart from said outer shell, tail pipes connecting the bottom of said inner and outer shells, respectively, and said hot well, a basin mounted in said inner shell, a bottom plate covering the top of said basin, water tubes secured in said plate and opening into said basin, a top plate secured to the upper end of said tubes, and spaced away from said inner shell, an inverted funnel mounted upon the said top plate and surrounding the upper ends of a plurality of said water tubes, a water pipe connected to said funnel, an expansion joint in said pipe, an exhaust pipe opening into said inner shell, and a suction pipe connected to said outer shell, substantially as described.
8. An apparatus of the character described, comprising a hot well, an outer shell mounted above said hot well at a greater height than a column of water balanced by atmospheric pressure, an inner shell supported in and spaced apart from said outer shell, tail pipes connecting the bottom of said inner and outer shells, respectively, and the two compartments of said hot well, a basin mounted in said inner shell, a bottom plate covering the top of said basin, water tubes secured in said plate and opening into said basin, a top plate secured to the upper end of said tubes, and spaced away from said inner shell, a hopper secured to said top plate and extending beyond the outer edge of the open top of said inner shell, an inverted funnel mounted upon the said top plate and surrounding the upper ends of a plurality of said water tubes, a water pipe connected to said funnel, an expansion joint in said pipe, an exhaust pipe opening into said inner shell, and a suction pipe connected to said outer shell, substantially as described.

said inner and outer shells, respectively, a basin mounted in said inner shell, a bottom plate covering the top of said basin, water tubes secured in said plate and opening into said basin, a top plate secured to the upper end of said tubes, and spaced away from said inner shell, a hopper secured to said top plate and extending beyond the outer edge of the open top of said inner shell, an inverted funnel mounted upon the said top plate and surrounding the upper ends of a plurality of said water tubes, a pipe connected to said funnel for supplying cooling water to said funnel, an expansion joint in said pipe, an exhaust pipe opening into said inner shell, and a suction pipe connected to said outer shell, substantially as described.

9. An apparatus of the character described, comprising a hot well divided into 20 two compartments, one for the cooling water and one for the distilled water, an outer shell mounted above said hot well at a greater height than a column of water balanced by atmospheric pressure, an inner shell supported in and spaced apart from said outer shell, deflectors arranged between said inner

and outer shells for directing the course of the cooling water, tail pipes connecting the bottom of said inner and outer shells, respectively, and the two compartments of 30 said hot well, a basin mounted in said inner shell, a bottom plate covering the top of said basin, water tubes secured in said plate and opening into said basin, a top plate secured to the upper end of said tubes, and spaced 35 away from said inner shell, a hopper secured to said top plate and extending beyond the outer edge of the open top of said inner shell, an inverted funnel mounted upon the said top plate and surrounding the upper 40 ends of a plurality of said water tubes, a water pipe connected to said funnel, an expansion joint in said pipe, an exhaust pipe opening into said inner shell, and a suction pipe connected to said outer shell, substantially as 45 described.

In testimony whereof, I affix my signature, in presence of two witnesses.

ADOLF KUYLENSTJERNA.
